DOORS OR COVERS FOR PRESSURE VESSELS
Henry Maurice Hattersley Pickard, Leeds, England
Application March 25, 1952, Serial No. 278,336
5 Claims. (Cl. 137—584)

This invention relates to doors or covers for pressure vessels, such as kiers, autoclaves, tanks, retorts, vulcanising pans and the like, of the kind described in British specification No. 412,700, wherein a series of pivoted latches disposed around the mouth of the vessel are adapted by partial movement of a ring to be swung into and out of the operative position to allow the door to be positioned and locked, the ring being mounted for rotational movement around the mouthpiece of the vessel.

In said specification there is described and claimed a positively acting safety device in the form of a relief valve which is maintained open so long as the door is in any position other than being completely closed. Such a safety device is generally satisfactory but it is possible for a slight pressure to be built up inside the vessel if the steam is turned on even if the door is not completely locked and consequently the relief valve still open. Even a slight pressure of only a pound or two may give rise to a considerable load on a large door.

The principal object of the present invention is to prevent such loads being built up on the door.

According to the invention, in a door or cover of the kind described, a valve controlling the supply of fluid under pressure to the interior of a vessel is associated with the actuating ring in such manner that the valve cannot be opened to admit fluid under pressure to the interior of the vessel until the door or cover has been fully locked.

According to the preferred embodiment, the said valve is link-connected with a rod or piston in such manner that the valve cannot be opened until said rod or piston has passed through an aperture in a plate rigidly associated with the actuating ring the arrangement being such that such passage of the rod or piston cannot occur until the actuating ring has assumed a position corresponding to the fully locked condition of the door or cover.

The invention will now be described with reference to the accompanying drawings, wherein:

Figure 1 is a perspective view of one form of the invention with the inlet valve closed.

Figure 2 is a corresponding view with the inlet valve open.

Figure 3 is a diagrammatic corresponding end view, and

Figures 4—6 are corresponding elevation, plan and end views of another embodiment.

Referring first to Figures 1—3, there is shown a door of the kind described in specification No. 412,700 and having associated therewith a safety device of the kind described therein, said safety device incorporating a relief valve A and operating mechanism B therefor. Such a safety device forms no part of the present invention although it is to be understood that it may be provided in addition to the safety device now to be described.

A valve 10 is provided in the pressure fluid inlet line 11, said valve being provided with an actuating handle 12, which extends radially from a cowling 13 which is rotatably supported by a bracket 14 secured to the wall of the vessel. A link 15 is secured to the lower end of the cowling 13 and said link is pivotally connected at 16 to a connecting rod 17 the other end of which is pivotally connected at 18 to a piston 19 which slides in a sleeve 20 carried by a plate 21 fixed to the mouthpiece of the vessel. A plate 22 is secured to the actuating ring 23 of the door, the plate 22 having an aperture 24 therein through which the piston 19 may pass when the ring

23 is in the position corresponding to the fully locked condition of the door. In the position of the parts shown in Figure 1, the door is not yet in the fully locked condition so that the valve 10 cannot be opened since the handle 12 is prevented from being turned by the engagement of the piston 19 with the plate 22. In the position shown in Figure 2, the ring 23 has turned to the position in which the door is fully locked, so that the valve 10 can be opened by rotation of the handle 12, the piston 19 passing through the aperture 24 in the plate 22.

The embodiment illustrated in Figures 4—6 is the same in principle as that illustrated in Figures 1—3, except that the inlet valve is located near the bottom of the vessel. In this case, a three-way valve 25 is provided, a link 26 being fitted to a square boss 27 on the valve spindle. The link 26 is pivotally connected at 28 to the connecting rod 17, the construction being otherwise the same as described with reference to Figures 1—3. When the handle 12 is in the position shown in full lines, the door is fully locked, the piston 19 has passed through the aperture 24 in the plate 22 and the valve 25 is in position to admit fluid under pressure to the interior of the vessel. With the handle 12 in the position shown in dotted lines, the door is not yet in the fully locked condition, so that the piston 19 is out of alignment with the aperture 24 in the plate 22, with the result that the handle 12 cannot be rotated into the position shown in full lines. In this position the pipe supplying fluid to the interior of the vessel is opened to atmosphere via the third port of the three-way valve 25. If desired, similar three-way valve may be used in connection with the embodiment shown in Figures 1—3. The provision of such a three-way valve is of advantage in preventing even a very small pressure being built up inside the vessel, due for example to leaky interior steam heating pipes, or the small pressure caused by the hot vessel warming up cold air trapped in the vessel when the door is closed.

I claim:

1. In a pressure vessel of the kind comprising a cover, pivotally mounted about a lateral hinge axis a series of pivoted latches disposed around the mouth of the vessel, and a ring mounted for rotational movement around the mouth of the vessel to swing said latches into and out of position to allow the cover to be locked after being swung into the closed position about said lateral hinge axis, the combination of a valve controlling the supply of fluid under pressure to the interior of the vessel, a plate rigidly associated with said ring, said plate having an aperture therein, a rod slidably mounted so as to be capable of passing through said aperture when in alignment therewith, and a link pivotally connected between said valve and said rod, said rod being in alignment with said aperture when said ring has assumed a position corresponding to the fully locked condition of the cover, and said valve being in the open position only after said rod has been passed through said aperture.

2. In a pressure vessel of the kind comprising a cover, pivotally mounted about a lateral hinge axis, a series of pivoted latches disposed around the mouth of the vessel, and a ring mounted for rotational movement around the mouth of the vessel to swing said latches into and out of position to allow the cover to be locked after being swung into the closed position about said lateral hinge axis, the combination of a valve controlling the supply of fluid under pressure to the interior of the vessel, a plate rigidly associated with said ring, said plate having an aperture therein, a sleeve fixed to said vessel adjacent its mouth, a rod slidably mounted in said sleeve so as to be capable of passing through said aperture when in alignment therewith, and a link pivotally connected between said valve and said rod, said rod being in alignment with said aperture when said ring has assumed a position corresponding to the fully locked condition of the cover, and said valve being in the open position only after said rod has been passed through said aperture.

3. A cover according to claim 1, wherein said valve is a three-way valve which, when not in position to admit fluid to the interior of the vessel, places said interior in communication with the atmosphere.

4. A pressure vessel having a mouth, a cover for said mouth pivotally mounted about a lateral hinge axis, a

series of pivoted latches disposed around said mouth, a ring mounted for rotational movement around said mouth to swing said latches into and out of position to allow the cover to be locked after being swung into the closed position about said lateral hinge axis, a valve controlling the supply of fluid under pressure to the interior of the vessel, a plate rigidly associated with said ring, said plate having an aperture therein, a sleeve fixed to said vessel adjacent its mouth, a rod slidably mounted in said sleeve so as to be capable of passing through said aperture when in alignment therewith, and a link pivotally connected between said valve and said rod, said rod being in alignment with said aperture when said ring has assumed a position corresponding to the fully locked condition of the cover, and said valve being in the open position only after said rod has been passed through said aperture.

5. A pressure vessel having a mouth, a cover for said mouth pivotally mounted about a lateral hinge axis, a series of pivoted latches disposed around said mouth, a ring mounted for rotational movement around said mouth to swing said latches into and out of position to allow the

cover to be locked after being swung into the closed position about said lateral hinge axis, a valve controlling the supply of fluid under pressure to the interior of the vessel, a plate rigidly associated with said ring, said plate having an aperture therein, a sleeve fixed to said vessel adjacent its mouth, a rod slidably mounted in said sleeve so as to be capable of passing through said aperture when in alignment therewith, and a link pivotally connected between said valve and said rod, said rod being in alignment with said aperture when said ring has assumed a position corresponding to the fully locked condition of the cover, and said valve being in the open position only after said rod has been passed through said aperture.
